UNITED STATES PATENT OFFICE.

RUDOLF KULLIG, OF ELBERFELD, PRUSSIA, GERMANY.

STEAM-TRAP.

SPECIFICATION forming part of Letters Patent No. 350,253 dated October 5, 1886.

Application filed February 24, 1886. Serial No. 193,087. (No model.) Patented in Germany May 12, 1885, No. 33,219; in England July 16, 1885, No. 8,615, and in Belgium December 14, 1885, No. 71,922.

To all whom it may concern:

Be it known that I, RUDOLF KULLIG, engineer, a subject of the King of Prussia, and a resident of Elberfeld, in the Kingdom of Prussia, Germany, have invented some new and useful Improvements in Steam-Traps, of which the following is a specification.

The object of these improvements is to remove the drawbacks contained in the so-called "Royle's Steam-Traps," which have been used hitherto.

In Royle's apparatus, working with a bell-shaped float, the lateral steam-inlet tube forms also the axis of the bell float, and the steam-tube and the float form together a stop-cock 15 in this manner, that by the rotating of the bell-float the steam-inlet tube is opened and closed, as if by a stop-cock. This method of closing the steam-tube, caused, as just said, 20 by the bell-float rotating on its axis, has the one great drawback that the closing soon becomes loose and admits steam, and is particularly unreliable under high steam-pressure. In the improvement described hereinafter this 25 evil is avoided by applying a valve in lieu of a stop-cock for closing the outlet-tube for the condensed water. It is applied in such a way that the bell-float, when rising, presses the valve firmly on its seat, which is formed by the 30 end of the steam-tube and closes the steam-inlet steam-tight.

The improvement is represented in Figures 1 to 6 of the drawings.

Like letters indicate like parts in all the 35 figures.

Fig. 1 is a vertical section through the line A B when the bell-float is in its highest position, in which case valve v is likewise in its highest position and the inlet-tube for the condensed water is closed. Fig. 2 is a vertical section through the line A B when the bell-float is in its lowest position, in which case valve v is lifted from its seat—that is to say, from the end f' of the steam-tube f , and the condensed water collected in the tube f escapes in the bell-float and the vessel M. Fig. 3 is a vertical section through the line C D. Fig. 4 is a top view of the steam-trap, the lid or cover m and the air-escape slide b being both removed. Fig. 5 (a section through the line A B) shows a part of the bell-float c , with the regulating-screw e

for valve v and balance-weight a , the steam-tube f , with its end f' . The steam-tube f is connected at its other end with the steam-conduit, out of which comes the condensed water that collects in tube f . Fig. 6 shows a section through the line $E F$, the tube f' , with the top view of valve v .

The construction and arrangement of the parts is as follows:

Part 3, as follows:—
M is a vessel open on top, with a steam-tube $f'f$ on the one side and an outlet-aperture on the other side. The vessel can be covered by a removable lid or cover, m , to prevent dirt, &c., getting into it. The end f' of the steam-tube f is bent downward, and into it is fixed a movable valve, v , which can either close or open the steam-inlet aperture. Valve v is made movable in the direction of end f' of the steam-tube and the guides that are attached to the valve and that encircle the end f' of the steam-tube, keep the valve always in the proper direction, so that it fits tight onto the end f' of the steam-tube every time if it is moved upward. This apparatus consists, further, of a bell-float, c , which is supported on the one side by bearers t and by means of axle s , round which it rotates. The bell-float c rests on the other side, as will be seen in the drawings, Fig. 2, on the bottom of the vessel M. In case the bell-float is made of cast-iron and requires balancing it can be provided with a balance-weight, a . This bell-float has on its upper side, just like the drain for the condensed water in Royle's apparatus, two little slits, o , which are covered by the littleslide b , attached to the rod n , and are always kept closed when the apparatus is working. These slits answer the same purpose as those in Royle's drain—that is to say, they allow the air to escape when the apparatus is started. This is done in the well-known way by lifting the slide b once only.

x are arms riveted fast to the bell-float *c*. The left arm bears the balance-weight *a*, and the right arm the screw *e*, which can be screwed either higher or lower in arm *x*, according as may be necessary. This screw serves as an adjusting-screw to make the valve *v* close properly in the desired position. 95

The way in which the apparatus operates is as follows: When the apparatus is not work-

ing, the parts are in the position indicated in Fig. 2. When the tube $f'f'$ is brought in connection with the steam-conduit, which is not represented in the drawings, the steam passes through the open aperture of the tube f' , fills the space in the bell, and forces the water contained in the latter downward and out of it. The bell begins to float and to rise, and the axle s forms the rotation-axis; but while the bell rises, the screw e , attached to arm x of the float, knocks against the valve v and presses it upward until the valve v is laid hard against tube f' and shuts the open end of it completely. No steam can then escape from the tube $f'f'$. The steam confined in the bell keeps it in its raised position, and valve v is shut by screw e . When the steam begins to condense, bell e will sink again, and valve v will be lifted off its seat f' , for screw e will relax in its pressure, whereas the pressure coming out of tube f' will force the valve v downward. If there is any condensed water in the tube $f'f'$, it will then flow out; but this water will not cause any alteration in the momentary position of

the float, for the condensed water cannot possibly raise the float. The float is not raised again before the condensed water has run out and steam begins to escape through tube f' . The bell rises again at once, valve v is again lifted—that is to say, tube f' is shut again—and the escape of steam prevented. The condensed water flows out from the vessel M through the aperture g . Screw e serves to regulate the proper closing of the valve v .

What I claim, and desire to secure by Letters Patent of the United States, is—

In steam-traps, the combination of a steam-tube, f , which runs into the vessel M and has its open tube end f' bent downward, with a valve, v , which is movable toward the said open tube end f' , and can open and shut it as necessary, and a rotating bell-float, e , which is suspended in the vessel M and has an arm, x , which closes the valve v .

RUDOLF KULLIG.
